UNITED STATES PATENT OFFICE.

EZRA DIXON, OF BRISTOL, RHODE ISLAND.

TOP-ROLL SADDLE.

No. 870,347.

Specification of Letters Patent.

Patented Nov. 5, 1907.

Application filed August 16, 1905. Serial No. 274,401.

To all whom it may concern:

Be it known that I, EZRA DIXON, a citizen of the United States, residing at Bristol, in the county of Bristol and State of Rhode Island, have invented a new and useful Improvement in Top-Roll Saddles, of which the following is a specification.

My invention has reference to an improvement in top roll saddles and more particularly to an improvement in the bearings of top roll saddles.

10 Top roll saddles as heretofore constructed with straight or parallel bearings create considerable friction on the journals of the top rolls, thus requiring an excess of power to run the top rolls of a spinning machine and more oil than should be necessary to lubricate the bearings of the top roll saddles.

The object of my invention is to eliminate friction (as near as possible) between the journals of the top rolls and the bearings of the top roll saddles, thereby increasing the life of the saddles.

20 A further object of my invention is to reduce the amount of oil required to lubricate the bearings of top roll saddles, thereby reducing the cost of lubricating the same.

My invention consists in the peculiar and novel construction of a top roll saddle for spinning machines, said top roll saddle having a roller bearing or its equivalent adapted to bear on the journal of a top roll, thus practically eliminating friction between the journal of the top roll and the bearing of the top roll saddle, as 30 will be more fully set forth hereinafter.

Figure 1 is a side view of the front and back top roll saddles provided with my improved anti-friction or roller bearings and showing the same in their operative position on the journals of the top rolls of a spinning machine. Fig. 2 is an enlarged view looking at the underside of the front and back top roll saddles, showing the roller bearings in the same. Fig. 3 is an enlarged sectional view taken lengthwise through the front and back top roll saddles on line *w w* of Fig. 2, 40 showing the means for oiling the roller bearings, and Fig. 4 is an enlarged transverse sectional view through the front top roll saddle taken on line *X X* of Fig. 1, showing the construction of the roller bearing in the same.

45 In the drawings, *a a* indicates the journals of the top rolls, *b* the back saddle, *c* the front saddle, *d d* oil grooves in the front and back saddles, *e e* oil wicks in the oil grooves, *f* weight strap, and *g g* the roller bearings of my improved front and back top roll saddles.

The back and front saddles *b* and *c* are each constructed to have the holes *d' d'* for the wicks *e e* leading from the grooves *d d* to the cavities *g' g'* formed in the underside of the saddles, as shown in Fig. 3. The lower edges of the side walls *g' g'* are shaped to conform to the journals *a a* of the top rolls. The saddles 55 have the outer countersunk portions *g' g'* for the plates *g' g'* which are shaped to conform to the contour of the saddles and secured to the saddles in the countersunk portions *g' g'* by the screws *g' g'*, as shown in Fig. 1 and Fig. 4. The rolls *g' g'* are rotatably secured in the 60 bearings *g' g'* formed in the side walls *g' g'* by boring two holes through the countersunk side wall *g'* and partly through the opposite side wall *g'*. The bearings *g' g'* thus formed intersect the lower edge of the side walls *g' g'* allowing the rolls *g' g'* when secured in 65 the bearings *g' g'* by the plate *g'* to project slightly through the lower edge of the side walls *g' g'*, as shown in Figs. 3 and 4, otherwise the front and back top roll saddles may have the construction of any of the well-known forms of top roll saddles. The ends of the 70 wicks *e e* project through the holes *d' d'* onto the rolls *g' g'* for lubricating the same.

In the use of my improved top roll saddles the wicks *e e* are oiled by the operator in the usual way. The wicks leading to the roller bearings *g' g'* lubricate the 75 bearings for a longer period with one oiling than has heretofore been done and the roller bearings *g' g'* practically eliminate friction between the journals of the top rolls and the bearing of the top roll saddles, thus reducing the power required to run the top rolls.

Having thus described my invention, I claim as new and desire to secure by Letters Patent;—

1. A back top roll saddle *b* constructed to have the cavities *g' g'*, the side walls *g' g'*, the countersunk portions *g' g'*, the plates *g' g'* secured in the countersunk portions *g' g'* by the screws *g' g'*, the rolls *g' g'* rotatably secured in the bearings *g' g'* formed in the side walls *g' g'*, the whole forming the roller bearings *g' g'* adapted to bear on the back and intermediate top roll journals of a spinning machine, and means for oiling the roller bearings *g' g'*, as described. 85

2. A front top roll saddle *c* constructed to have the cavity *g'*, the side walls *g' g'*, the countersunk portion *g'*, the plate *g'* secured in the countersunk portion *g'* by the screw *g'*, the rolls *g' g'* rotatably secured to the bearings *g' g'* in the side walls *g' g'*, the whole forming the roller bearing *g'* adapted to bear on the front top roll journal of a spinning machine, and means for oiling the roller bearing *g'*, as described. 95

3. The combination of a back top roll saddle *b* constructed to have the cavities *g' g'*, the side walls *g' g'*, the countersunk portions *g' g'*, the plates *g' g'* secured in the 100

countersunk portions g^3 g^8 by the screws g^5 g^6 , the rolls g^6 g^9 rotatably secured in the bearings g^7 g^7 formed in the side walls g^2 g^2 , the whole forming the roller bearings g g adapted to bear on the back and intermediate top roll journals of a spinning machine, and a front top roll saddle c constructed to have the cavity g^1 , the side walls g^2 g^2 , the countersunk portion g^3 , the plate g^4 secured in the countersunk portion g^3 by the screw g^5 , the rolls g^6 g^9 , rotatably secured in the bearings g^7 g^7 in the side walls g^2 g^2 , the whole forming the roller bearing g adapted to

bear on the front top roll journal of a spinning machine, and means for oiling the roller bearings g g in the back and front saddles b and c , as described.

In testimony whereof I have signed my name to this specification in the presence of two subscribing witnesses. 15

EZRA DIXON.
